JOHN TAYLOR AND JOSEPH E. KOHN, OF CLEVELAND, OHIO, ASSIGNEES TO
THE KILBY MANUFACTURING COMPANY, OF SAME PLACE.

ROTARY DRIER.

SPECIFICATION forming part of Letters Patent No. 664,187, dated December 18, 1900.

Application filed May 22, 1899. Serial No. 717,812. (No model.)

To all whom it may concern:

Be it known that we, JOHN TAYLOR and JOSEPH E. KOHN, residents of Cleveland, Ohio, have invented certain new and useful Improvements in Rotary Driers; and we do hereby declare the following to be a full, clear, and exact description of the invention, such as will enable others skilled in the art to which it pertains to make and use the same.

Our invention relates to improvements in steam-driers, and more especially to a machine for drying sugar.

The primary object of our invention is to provide a sugar-drier that is simple and inexpensive in construction, durable, and convenient.

With this object in view the invention consists in certain features of construction and combinations of parts hereinafter described, and pointed out in the claims.

In the accompanying drawings, Figure I is a side elevation, mostly in central section, of a sugar-drier embodying our invention. Fig. II is a forward end elevation, mostly in transverse vertical section, taken centrally through the forward head *g* of the cylinder *a*. Fig. III is a forward end elevation, mostly in transverse vertical section, taken through the cylinder *a* and the internal tubes *l* of the said cylinder at the inner side of the tube-connecting head *k*. Fig. IV is an enlarged section in detail on line IV IV, Fig. III. Fig. V is an enlarged section in detail on line V V, Fig. III. Fig. VI is a section in detail on line VI VI, Fig. V. Fig. VII is a side elevation, mostly in central longitudinal section, of the machine, and in this figure the parts are shown on a larger scale than in Figs. I, II, and III and portions are broken away to reduce the size of the drawings. Fig. VIII is a forward end elevation of a portion of the machine in section on line VIII VIII, Fig. VII.

Referring to the drawings, *a* designates a rotary drying-cylinder declining somewhat toward its rear or discharging end. The cylinder *a* is mounted upon any suitable number of suitably-supported and suitably-arranged rollers *a'*. The cylinder *a* at its forward or receiving end is provided with a cylinder *b*, that is diametrically smaller than cylinder *a* and suitably attached to and con-

sequently rotates with the cylinder *a* upon the rotation of the latter. Cylinder *b* is arranged in line with and consequently declines toward the cylinder *a* and is open at its rear end and there communicates with the forward end of the chamber of the cylinder *a*. The cylinder *b* is provided at its forward end with a head *d'*, (see Figs. VII and VIII,) that has an induction-aperture *d*², adapted to receive the sugar that requires drying from a screw conveyer *c*, that is arranged horizontally within a stationary case *d*, that is open at the top. The head *d'* is rigid with the case *d*, and consequently stationary, and the cylinder *b* rotates upon the head *d'*. The latter is provided also with a spout *d*³, that is in open relation with the chamber of the case *d* at the aperture *d*². The head *d'* is provided also with a manhole *d*⁴ for affording access to the cylinder *b* and has another hole or aperture *d*⁵ for affording escape of currents of hot air that may be forced or introduced into the cylinder *a* at the latter's rear end.

The shaft *c'* of the screw conveyer is operatively provided forward of the conveyer-case with a sprocket-wheel *c*², that is operatively connected, by means of a chain *c*³, with a sprocket-wheel *e'*, operatively mounted upon a driving-shaft *e*, to which power is applied in any approved manner. The shaft *e* is rotated in the direction of the arrow and is arranged horizontally and longitudinally of and below the cylinder *b*. The shaft *e* below the rear end of the cylinder *b* is operatively provided with a pinion *e*², that meshes with a spur-gear *f*, formed upon the exterior of an annular casting *g*, that has bearing upon several rollers *a'*. Preferably the forward end of the cylinder *a* and the rear end of the cylinder *b* are secured to the said casting *g*, so that the latter forms the connection between the cylinders *b* and *a*.

The casting *g* is hollow and has an annular internal chamber *g'*. The axes of the cylinders *a* and *b* are coincident. The casting *g* closes the forward end of the cylinder *a* around the rear end of the cylinder *b*, and consequently forms a hollow annular head for the forward end of the cylinder *a*.

The annular chamber *g'* within the head *g* is a steam-chamber. A steam-pipe *h* extends

centrally and longitudinally through and is coincident with the axis of the cylinder a . Pipe h at the forward end of the cylinder a has two branches h' and h'' arranged diametrically opposite each other and radially of the cylinder a . Branch pipes h', h'' are attached at their outer end to the head g and are in open relation with the chamber g' , formed within the said head. The pipes h', h'' are connected and in open relation at their inner ends by a T h^3 with the pipe h . Cylinder b has two internal transversely-arranged braces b^2 b^3 , arranged a suitable distance apart longitudinally of the cylinder and provided at the axis of the cylinder with boxes b^3 , affording bearing for the pipe h .

In the case illustrated the conveyer-case d and the connected spout d^3 are arranged at one side of the pipe h .

20 The pipe h is in open relation at its outer or receiving end with the steam-supply pipe i , that is held stationary in any approved manner. The pipe h rotates with the cylinders, and to prevent leakage between the said pipe and the steam-supply pipe i a stuffing-box j is provided at the joint between the said pipes, which box embraces the steam-supply pipe and is supported from and rotates with the pipe h .

30 An annular head-forming casting k is supported centrally of and within the rear end of the cylinder a . The said casting is hollow and provided internally with a chamber k' , that is arranged concentrically or circumferentially of the axis of the cylinder and has its ends separated by a diaphragm or partition k^2 , that extends transversely of the casting and interrupts communication between opposite ends of the chamber k' . The chamber 40 of the head k is placed in open relation with the chamber of the head g by a series of tubes l , extending longitudinally of the cylinder a between the said heads.

The series of tubes l in the case illustrated 45 comprises twenty-four tubes that are arranged at equal intervals circumferentially of the cylinder. The said tubes are secured to the heads in any approved manner. The tubes are parallel with the cylinder a , and hence decline in a rearward direction. The 50 rear tube-connecting head k is provided with several radial arms k^3 , arranged at equal intervals and suitably connected together at their inner ends by a web k^4 , and the said head is suspended at the aforesaid arms from the head-surrounding portion of the cylinder a . In the case illustrated the rear head has 55 four arms k^3 . Each arm upon its outer side is provided with a lug k^5 , that is connected with the cylinder a by a rod k^6 , arranged radially of the cylinder. The head k is therefore supported within the rear portion of the cylinder by four radially-arranged rods that are secured at their outer ends to the cylinder 60 and are secured at their inner ends to the correspondingly-arranged arms of the said head.

The forward side of the diaphragm or partition k^2 is that side which faces in the direction in which the head k and the cylinder a 70 rotate during the operation of the machine. The double-headed arrow in Fig. III indicates the direction in which the said head rotates. The chamber k' of the head k next forward of the diaphragm or partition k^2 and at the 75 inner side of the chamber is connected in any approved manner with a system of drain-pipes, which system comprises a pipe m , that extends rearwardly from the axis or central portion of the head k . A revolving screen s , 80 that is preferably somewhat larger diametrically than the cylinder a , surrounds the pipe m and is suitably secured to the rear end of the cylinder. Some of the sugar that is being dried in its passage through the 85 screens is too coarse or lumpy for the mesh of the screen and is discharged at the screen's rear end, whereas the finer sugar passes through the mesh of the screen into a hopper or receptacle r , provided below the screen. 90

The pipe m is provided at its inner end with an external annular flange m' , that is suitably secured to the arm-connecting web k^4 of the head k , and is in open relation with an aperture k^7 , formed within and centrally 95 of the said web. The web is provided upon its inner side with a boss k^8 , that projects laterally or radially of the cylinder a , and has the hole k^9 , that is formed therein, open at the outer end of the boss and in open relation at 100 its inner end with the aperture k^7 , formed in the web. The said boss is provided at its outer end with an external annular flange k^{10} . A boss k^{11} is formed upon the inner periphery of the head k , adjacent to the diaphragm or partition k^2 , and has its hole k^{12} in open relation with the chamber k' next forward of the said diaphragm or partition. A curved pipe k^{13} extends between the said 105 boss k^{11} and the aforesaid boss k^8 and is arranged approximately radially of the head k . The pipe k^{13} is provided at its inner end with an external annular flange k^{14} , that is secured to the flange k^{10} , and the pipe k^{13} at its opposite or outer end is provided with an 110 external annular flange k^{15} , that is secured to the outer end of the boss k^{11} . The curved pipe k^{13} , together with the connections between it and the head k and the pipe m , forms a passage-way between the discharging end 115 of the chamber of the head k and the pipe m .

The pipe m rotates, of course, with the cylinder. The said pipe at the rear end of the screen is in open relation and connects with the drain-pipe m^2 , that is held stationary in 120 any approved manner. To prevent leakage between the pipe m^2 and the connected pipe m , a stuffing-box m^3 is provided, which box embraces the pipe m^2 and is supported from the pipe m .

The operation of the machine will be readily understood. The cylinder a and the parts that rotate or revolve with the cylinder are actuated by motion transmitted from the driv-

ing-shaft *e* through the intergearing between the said shaft and the cylinder. The screw conveyer *c* discharges sugar into the cylinder *b*, wherein the sugar is dried in a measure. 5 The sugar passes from the cylinder *b* into and through the steam-heated chamber of the cylinder *a* into the screen. Too much moisture with the sugar upon the latter's passing into the cylinder *a* would result in the adhesion 10 or sticking of sugar upon the tubes, and hence partially drying the sugar before the introduction of the sugar into the cylinder *a* is desirable. The steam passes from the steam-supply pipe *i* into the pipe *h*, thence is conducted 15 by the branch pipes *h' h'* into the forward head *g* of the cylinder, and thence the steam passes into the rearwardly-extending tubes *l*. A large portion of the steam will have condensed before reaching the rear head *k*, and some will 20 condense within the said head, and the water resulting from the condensation of the steam is discharged into the drain-pipe system at the discharge opening or outlet *k¹²* next forward of the diaphragm or partition of the said 25 head *k*.

Our improved machine is more especially distinguished from sugar-driers heretofore made by the simplicity, convenience, efficiency, and durability of its peculiar construction that forms the subject-matter of this 30 application.

What we claim is—

1. A drier of the character indicated, comprising a rotary cylinder declining in a rearward direction; a series of declining tubes arranged longitudinally within, and at suitable intervals circumferentially of, the cylinder; means for supplying steam to the forward ends of the said tubes; means for draining 35 the tubes at their rear ends; another rotary cylinder connected with the forward end of and arranged in line with the first-mentioned cylinder and provided, at its forward end, with a stationary head having an inlet for the 40 material requiring drying, a steam-pipe extending centrally through and arranged axially of the forward cylinder, and terminating, at the rear end of the said forward cylinder, in branch pipes connected and in open relation with the forward ends of the aforesaid 45 tubes.

2. A drier of the character indicated, comprising a rotary cylinder declining in a rearward direction; a series of declining tubes arranged longitudinally within and at suitable intervals circumferentially of the cylinder; another rotary cylinder connected with the forward end of, and arranged in line with, and diametrically smaller than, the first-mentioned cylinder; a hollow head surrounding the rear end of the forward cylinder and closing the rear and tube-containing cylinder at the latter's forward end around the forward cylinder, which head is suitably secured to and 55 forms the connection between the cylinders; a steam-pipe extending centrally through and

axially of the forward cylinder and connected and in open relation, at the rear end of the said cylinder, with the chamber of the aforesaid head, and the braces *b²* internally of the 70 said forward cylinder and provided with boxes *b³* affording bearing for the said steam-pipe, substantially as and for the purpose specified.

3. In a drier of the character indicated, the combination, with a rotary cylinder; a system of tubes arranged longitudinally within and at suitable intervals circumferentially of the cylinder, and means for supplying steam to the forward ends of the said tubes; of an annular head supported within the rear 80 end of the cylinder and having a continuous chamber extending circumferentially of and around the cylinder and in open relation with the rear ends of the aforesaid tubes; a partition or diaphragm arranged transversely of 85 and within the head and interrupting endless continuity in the said chamber circumferentially of the cylinder, and a drain-pipe system comprising a passage-way that is in open relation with the said chamber adjacent to 90 that side of the aforesaid diaphragm or partition that faces in the direction in which the cylinder and the aforesaid head rotate during the operation of the machine.

4. In a drier of the character indicated, the combination with a rotary cylinder; a series of tubes arranged longitudinally within and at suitable intervals circumferentially of the cylinder, and means for supplying steam to the forward ends of the said tubes; of an 100 annular chambered head supported within the rear end of the cylinder and having radial arms extending from the head's inner periphery inwardly, which head has its chamber in open relation with the aforesaid tubes; a 105 drain-pipe system connected with the said chamber; means instrumental in conducting water accumulating within the said chamber into the drain-pipe system, and rods arranged radially of the outer side of the aforesaid 110 head, which rods are connected, at their inner ends, to the arms, and have their other ends connected to the cylinder.

5. In a drier of the character indicated, the combination, with a rotary cylinder, a series 115 of tubes arranged within and longitudinally of the cylinder, and means for supplying steam to the forward end of the said tubes, of an annular head *k* supported centrally of the rear end of the cylinder and having a chamber 120 extending circumferentially of the said cylinder and in open relation with the rear ends of the aforesaid tubes, which head is provided with the internal diaphragm or partition *k²* interrupting continuity in the aforesaid chamber circumferentially of the cylinder, a boss *k¹¹* formed upon the inner periphery of the said head adjacent to the diaphragm or partition and having the hole therethrough 125 in open relation with the chamber of the head 130 next forward of the said diaphragm or partition, and a system of drain-pipes connected

and in open relation with the interior of the said boss, substantially as and for the purpose set forth.

6. In a drier of the character indicated, the combination with a rotary cylinder, a series of tubes arranged within and longitudinally of the cylinder, and means for supplying steam to the forward ends of the said tubes; of an annular head k supported centrally of the rear end of the cylinder, and having a chamber extending circumferentially of the cylinder and in open relation with the rear ends of the aforesaid tubes, which head is provided with the diaphragm or partition k^2 ,
15 the boss k^{11} , the radial arms k^3 , the web k^4 ,

and the boss k^8 ; the system of drain-pipes connected and in open relation with the chamber of the last-mentioned boss, and a pipe or passage-way connecting together and establishing open relation between the aforesaid 20 bosses, all arranged and operating substantially as shown, for the purpose specified.

Signed by us at Cleveland, Ohio, this 17th day of May, 1899.

JOHN TAYLOR.
